REGISTER

Robert N. Ward and Herman F. Sadgebury, Dayton, Ohio, assignors to The Egry Register Company, Dayton, Ohio, a corporation of Ohio

Application February 25, 1946, Serial No. 649,880

3 Claims. (Cl. 282—16)

1

This invention relates to paper handling machinery and, particularly, to registers such as counter registers employed for recording individual sales.

One object of this invention is to provide a construction of such a register in which the paper handling mechanism may be removed as a unit and mounted in another frame if desired.

Another object is to provide a register having a case and operating equipment therein which is mounted on a subframe that is removed from and inserted into the case as an integral unit.

Still another object is to provide a register having a case and a removable paper handling unit therein that is divided into two compartments.

Still another object is to provide a register according to the foregoing objects in which carbon paper is supplied between the sheets passing through the register from a compartment within the case of the register.

A still further object is to provide an improved means for disengaging the paper feed rolls from the paper to permit alignment of the paper and to permit the paper to be removed or inserted.

These and other objects and advantages will become more apparent upon reference to the following description and accompanying drawings in which:

Figure 1 is a perspective of a register according to this invention as it would appear in operation;

Figure 2 is a view similar to Figure 1 but showing the register open;

Figure 3 is a longitudinal section taken substantially in the plane 3—3—3 as indicated on Figure 1;

Figure 4 is a transverse view taken substantially along the line 4—4 of Figure 3;

Figure 5 is a plan view over the register with portions thereof removed;

Figure 6 is a view taken substantially along the line 6—6 of Figure 5 and shows the manner of feeding the carbon paper between the record sheets;

Figure 7 is a fragmentary view showing how the original and duplicate of the written sheets are divided, one to fall within the register and the other to be removed therefrom;

Figure 8 is a view taken on the line 8—8 of Figure 4 and shows the register handle and the stop means associated therewith by which the rotation of the handle is normally limited to a single revolution;

Figure 9 is a fragmentary view showing the

2

means for locking the register in a closed position;

Figure 10 is an enlarged view illustrating the paper feed rolls;

Figure 11 is a fragmentary view taken on the line 11—11 of Figure 5 showing the drive between the shaft of the crank and the paper rolls;

Figure 12 is a view taken on the line 12—12 of Figure 5 and showing the mechanism for separating the paper feed rolls when it is desired to release the paper from them; and

Figures 13 and 14 are views illustrating the mechanism for stopping the paper aligning pins in operative position and for releasing them when a feeding movement is commenced.

Referring to the drawings, and particularly to Figures 1 through 5, a register constructed according to this invention comprises an outer case generally indicated at 10 which includes a lid 12 pivoted at 14 and enclosing the duplicate copy compartment. The case also has a lid 16 pivoted at 18 and enclosing a compartment containing a supply of form to be used. Also pivoted at 18 is a writing table 20 over which the papers to be written on are drawn by a paper feed mechanism generally indicated at 22. Access to the forms is had through an aperture 24 in the lid 16, the aperture being of such a size that the entire form may be inscribed if necessary without moving the paper.

To supply carbon for transferring the written information to the duplicate or duplicates in the machine there is provided a pair of brackets as at 26 and 28 supported on the inside of one side wall of the register case 10 and detachably supporting a carbon feed roll 30. As seen in Figure 6, the carbon sheets 32 may be drawn from the carbon feed roll 30 and passed between the paper sheets 34 and thence to the exterior of the case at the other side. At the said other side there is a bar 36 which is pivoted at 38 and latched at its other end by a spring pressed latch 40. The bar 36 may be released so that the end of the carbon sheets may be grasped and a new writing area drawn across the table 20. Thereafter, the bar 36 is returned to its Figure 5 position and serves as a tearing edge for removing the used carbon. The writing table 20 is supported in its writing position by resting at one side on the bracket 26 and at the other side on a pair of tabs 42 which are turned out from a bar 44 secured to the side wall of the case 10.

After the forms have passed through the paper feed mechanism at 22, they may be divided, as

shown in Figures 3 and 7, by the edge 46 of the lid 12 so that one or more thereof passes through to the outside of the register and one or more thereof will fall inside the register. The forms which pass out of the register may be torn off against a suitable edge and disposed of as desired.

The forms are supplied to the writing table 20 from the supply compartment through an aperture 48 in the said table and over a roller 50 which prevents the folds in the forms from snagging on the edge of the table 20.

The supply compartment is generally indicated at 52 while the compartment which receives the written duplicates is generally indicated at 54. A divider plate 56 which has a paper guiding portion at 58 separates the compartments one from the other while a channel-shaped or U-shaped sub-frame indicated at 60 and having the side walls 62 and 64 forms the bottom and side walls for the said compartments.

The sub-frame 60 together with the divider plate 56 are secured to the casing 10 by suitable detachable means such as the nuts and bolts indicated at 66. By removing the nuts and bolts the entire sub-frame may be lifted from the register case as a unit.

To further unify the mechanism which is removable from the case, the sub-frame 60 supports the paper feed mechanism 22. The said feed mechanism comprises an upper roll 68 and a lower roll 70 which are drivingly connected by the gears 72. As best seen in Figure 10, the lower roll 70 has its ends journaled in a pair of plates 74 that are rigidly mounted on the side walls of the sub-frame. The upper roll 68 has the ends of its shaft journaled in the plates 76 which lie against the plates 74 and are reciprocable relative thereto in a vertical direction. The screws, springs and nuts shown at 78 continuously urge the bars 76 downwardly and thus urge the rolls into paper gripping position. Access may be had to the aforementioned nuts through apertures 80 in the register case so that the thrust of the springs may be adjusted.

The lower feed roll 70 is driven through a gear train, as shown in Figure 11, forming shaft 82 connected with the crank 84 which is secured to the said shaft externally of the case 10. The first gear in the gear train has associated therewith a ratchet 86 which is pivoted on the side wall 64 of the sub-frame 60 and engages with the said gear in order to permit rotation thereof in one direction only. This gear train is indicated at 88 and drives directly into the lower of the gears 72. It will be noted that the lower of the gears 72, that is the one connected with the feed roll 70, is considerably larger than the gear 72 connected with the feed roll 68. Thus, the feed roll 68 operates at a greater speed and is correspondingly smaller.

For aligning the paper at the end of each feeding operation, the shaft of the feed roll 68 mounts a pair of sleeves 90 that include the roller tipped plungers 92 which lie directly in the path of the file holes 94 in the paper forms. Friction clutch means at 96 serve continuously to urge the sleeves 90 to rotate with the feed roll 68. Each of the sleeves 90 carries at its outer end a cam portion 98, better seen in Figures 13 and 14. The cams are substantially aligned with the pins 92 and are of such a size that they will engage the lower of the feed roll shafts and separate the said rolls when in their Figure 13 position. In this position a latch arm 100 which is secured to cross

shaft 102 carried in the sub-frame 60 engages and halts rotation of the said sleeves.

One of the arms 100 has connected therewith a spring 104 which continuously urges the said arms to engage the cams and the one of the arms adjacent the first of the drive gears 88 has a surface as at 106 adapted for engagement by a pin 108 carried by the said gear. When the pin 108 engages the surface 106, the cams 98 are released and permit the sleeves 90 to rotate with the shaft of the feed roll 68.

To insure that the feed rolls will always stop in their Figure 13 position, the crank 84 connected with the shaft 82 has a stop pin 110 that is carried on a plate 112. The stop pin 110 lies normally in position to be engaged by a stop pin 114 on the case 10, and this engagement comes about when the parts are in their Figure 13 position. Thereafter, when it is desired to feed paper the plate 112 is moved to disengage the pins 110 and 114 and the crank 84 is turned until the pins again abut.

By the arrangement set forth above, the roll 68 and the sleeves 90 rotate more rapidly than roll 70 and bring the plungers 92 into engagement with the form a substantial period of time before the file holes therein reach the said plungers. Thereafter, the sleeves 90 remain stationary until the file holes become aligned with the said plungers, whereupon the sleeves 90 again rotate until they are halted in their Figure 13 position. This accurately aligns the forms in the same position each time the crank is operated.

To separate the feed rolls manually, the plates 76 and 74 are connected by an eccentric mechanism at 116 which is operated by lever 118. The reciprocable plates 76 have an elongated slot 120 therein such that the plate 76 reciprocates freely in normal operation but is lifted to separate the feed rollers when the arm 118 is manually rotated. By means of this mechanism the rollers may be separated to permit the paper to be initially fed in or to be removed from the machine.

The minimum spacing of the feed rollers are limited by cooperating collars as at 122 carried at each end of the shafts and adapted for engagement to prevent wearing contact of one of the feed rollers on the other.

When the register is in its closed position the lid 12 is supported by the edge of the frame 10 and the lid 16 is supported on the lid 12 by means of the pins 124 carried by the said lid 16 and overlying the edge of the lid 12. To retain the register closed, the lid 16 comprises dependent portions 126 which are apertured to receive the latches 128 that are pivoted on a cross shaft 130. At one side of the register there is an arm 132 having a nose which engages the back of the latch member 128 on that side. The arm 132 also comprises a roller adapted for engagement with the plunger of a lock mechanism 134. When the lock is locked, the arm 132 is rotated thereby to urge the latch member 128 into engagement with the depending portions 126. When the lock is unlocked, a spring 136 withdraws the latch members and permits the lids to be opened.

The copy sheets which are delivered to the compartment 54 normally fall into their proper folded position and are assisted in this by the ball 138 which is suspended from the lid 12. However, should the copies not fold correctly into the compartment or should the compartment become too full to receive other copies, a second

ball 140 is also suspended from the lid and is adapted for movement by a knurled thumb wheel 142 to compress the pack to permit further sheets to be supplied thereto.

To facilitate the removal of the record pack in the compartment 54 there is a thin metallic sheet as at 144 which extends from the divider plate 56 to overlie the lower lid 12. Then, when the lid 12 is opened, the record pack is lifted from the floor of its compartment and may readily be grasped to be removed.

It will be seen that this invention provides for a register of the counter type which is readily loaded and unloaded, which maintains the paper properly aligned at all times, and which has the operating mechanism thereof independently supported in a sub-frame which is detachable from the register case. By this last provision, the paper handling mechanism may be readily adapted to forms of different lengths or mounted in cases of different design, or finished as a unit to be inserted in a case according to the individual preference of the user.

It will be understood that this invention is susceptible to modification in order to adopt it to different usages and conditions and, accordingly, it is desired to comprehend such modifications within this invention as may fall within the scope of the appended claims.

We claim:

1. In an autographic register comprising an outer case having a base, ends, side walls and a movable lid, a pivoted writing table located beneath said lid, a sub-frame having a base extending along said case base and having side walls lying in spaced parallel relationship to said case side walls, means for removably attaching said case and sub-frame to each other, a partition in said sub-frame dividing the same into paper supply and paper receiving compartments, paper feed means carried by said sub-frame including rollers, gearing mounted on one of said sub-frame side walls, and a crank having a shaft extending through said last named side walls and drivingly connected to said gearing, said sub-frame having open ends and said paper feed means being mounted substantially midway between the open ends of said sub-frame.

2. In an autographic register comprising an outer case having a base, ends, side walls and a movable lid, a pivoted writing table located beneath said lid, a sub-frame having a base extending along said case base and having side

walls lying in spaced parallel relationship to said case side walls, said sub-frame being of channel shape and extending substantially the length and height of said outer case, means for removably attaching said case and sub-frame to each other, a partition in said sub-frame dividing the same into paper supply and paper receiving compartments, paper feed means carried by said sub-frame including rollers, gearing mounted on one of said sub-frame side walls, and a crank having a shaft extending through said last named side walls and drivingly connected to said gearing, said sub-frame having open ends and said paper feed means being mounted substantially midway between the open ends of said sub-frame.

3. In an autographic register comprising an outer case having a base, ends, side walls and a movable lid, a pivoted writing table located beneath said lid, a sub-frame having a base extending along said case base and having side walls lying in spaced parallel relationship to said case side walls, means for removably attaching said case and sub-frame to each other, a partition in said sub-frame dividing the same into paper supply and paper receiving compartments, paper feed means carried by said sub-frame including rollers, gearing mounted on one of said sub-frame side walls, and a crank having a shaft extending through said last named side walls and drivingly connected to said gearing, said sub-frame having open ends and said paper feed means being mounted substantially midway between the open ends of said sub-frame.

ROBERT N. WARD.
